UNITED STATES PATENT OFFICE.

LOUIS PEROTTI, OF NEWARK, NEW JERSEY.

LIQUID-DISTRIBUTER.

SPECIFICATION forming part of Letters Patent No. 788,118, dated April 25, 1905.

Application filed November 18, 1904. Serial No. 233,363.

To all whom it may concern:

Be it known that I, LOUIS PEROTTI, a subject of the King of Italy, and a resident of Newark, in the county of Essex and State of New Jersey, have invented certain new and useful Improvements in Liquid-Distributers, of which the following is a specification.

- The present invention relates to improvements in liquid-distributers, particularly in medicine-distributers of the kind described in my previous application filed May 13, 1904, Serial No. 207,868, and has for its object to provide for a bottle appliance that will permit the discharge of a liquid or a medicine in prescribed quantities, as a table-spoonful or teaspoonful, and will prevent an overdosing of the medicine and the spilling out of the same on the floor or the clothes of the person taking the medicine.
- This invention has also for its object to provide for a liquid-distributer that will at the same time serve as a stopper and will replace the ordinary corks used heretofore.

Another object of my present invention is to avoid the necessity of spoons which in most cases are used for taking in meals, tea, &c.

In order to make my invention more clear, the same is illustrated in the accompanying drawings, in which similar letters denote similar parts, and in which —

Figure 1 is a vertical section of the medicine-distributer, showing the same as applied to a bottle. Fig. 2 is a similar section showing the distributer in a position when the bottle is reversed. Fig. 3 is a similar section showing the distributer in a position in which the medicine can be taken. Fig. 4 is a top view of the medicine-distributer. Figs. 5 and 6 illustrate a cross-section through line xx of Fig. 1, showing the rubber valve-body closed and opened, respectively.

With reference to the drawings, a denotes an ordinary medicine-bottle; b , its neck, which is closed by a stopper, forming a part of the medicine-distributer, instead of by the ordinary corks. The stopper consists of a relatively narrow glass tube d , having on its outer surface a cork cover c , that will in its circumference be somewhat larger than the mouth e of the bottle, so as to offer a tight closure of

the latter. At its top the glass tube d is provided with a head e of a somewhat larger circumference than the first and serves for the attachment of the distributer proper. The latter consists of a hollow glass bulb g , preferably of spherical shape, having at its lower side a hollow cylindrical neck h and at its opposite side a conical nozzle i . A peculiarly-shaped body m , of elastic material, preferably of rubber, connects the glass bulb g with the stopper d and serves at the same time as a valve between the bottle and the glass bulb. For this end the body m is at its lower end partially ball-shaped and provided with an excavation n , by which the head e of the glass tube d is engaged when it is pressed into the same. In order to provide for a stronger connection between these two parts, a groove o is cut around the circumference in the head e of the glass tube, into which the flesh of the rubber body m will engage when the latter is drawn over it, and owing to the strong contractibility of the rubber body the two parts will be securely and tightly held together. The upper end p of the rubber body is formed to a cylindrical neck of such a size as to tightly fit into the hollow neck h of the glass bulb g . At its lower end the neck p is provided with a circular rib j , projecting inward thereof and adapted to catch around the neck p of the rubber body m , and thus also form a strong and tight joint. The rubber body is provided with a longitudinal passage q arranged in the neck, this passage being open at its upper end. At its lower end the passage is separated from the excavation or gorge n of the body m by a thin partition r , in which through the central line of the passage q a straight single cut s is made, Fig. 5. Owing to the contractibility of the material of the body m , the cut s will normally form a tight closure of the lower end of the passage q , and the liquid in the bottle when the latter is reversed will not be allowed to pass from the gorge n into the bulb g ; but when a lateral pressure is exerted upon the rubber body m longitudinally of the cut s in the direction of the dotted lines $y y$ of Fig. 5 the compression of the body will cause the separation of the parts between which the cut s is made and an open-

ing *t* will be formed that will connect the passage *r* in the glass tube *d* with the passage *q* of the rubber body *m*, hence the bottle *a* with the glass bulb *g*, and thus allow the liquid or 5 medicine to flow into the latter. To close up the glass bulb *g* before the liquid can be allowed to fill the same, a glass ball *l*, that will exactly fit over the inner open end of the nozzle *i*, is arranged. Just at one side of the 10 nozzle the bulb *g* is provided with a hollow hump *k*, adapted to receive the glass ball, the arrangement being made so that when the bottle is reversed the glass ball *l* will rest over the nozzle and when the bottle is tilted over 15 into a position in which the medicine can be easily taken the ball will roll over the shoulder *u*, formed between the nozzle *i* and the hump *k*, and fall into the latter, Fig. 3, in which it will rest as long as the medicine is taken. 20 When the bottle is again reversed and placed in the normal position, the ball *l* will adopt the position shown in Fig. 1 in full lines.

The glass bulb is preferably made of such a size that its volume will be equal to that of a 25 table-spoon, while a mark *w* on the outside of the glass body *g* may denote the volume of a teaspoon.

It will be clearly seen that when a prescribed quantity of the liquid is to be taken 30 (a table or tea spoonful) and the present liquid measurer or distributor is applied to the bottle in the above described manner the bottle is reversed so that the ball *l* will close up the glass bulb *g*, as shown in Fig. 2. Then 35 the passage *q* is opened by the compression of the rubber body *m*, allowing the liquid to fill the bulb with the described quantity, and as soon as this is attained again closed by relieving the body *m*. The bottle with the liquid-measurer is then so tilted that the ball *l* 40 will fall into the hump *k* and open the bulb, so that the liquid can be directly discharged into the mouth of the patient.

At the lower part of the glass bulb, around 45 the neck *h* thereof, one or more openings may be arranged for the access of air, which is necessary to allow a free discharge of the liquid.

It is understood that any changes in the various parts of my present invention may be 50 made without departing from the spirit of my invention.

What I claim, and desire to secure by Letters Patent, is—

1. In a liquid or medicine measurer or distributor, the combination with a hollow stopper fitting into the mouth of a bottle, of a glass bulb of a predetermined size to receive a prescribed quantity of the liquid, said bulb having at one end a discharge-opening and at 55 its opposite end an open connection with the stopper, means for connecting the stopper with the glass bulb, and a valve to close the discharge-opening of the glass bulb, substantially and for the purpose as specified.

65 2. In a liquid or medicine measurer the com-

bination with a hollow stopper fitting into the mouth of a bottle, of a glass bulb of a predetermined size to receive a prescribed quantity of the liquid, a connecting-piece attached at one end to the stopper and at the opposite end 70 to the glass bulb, said piece being of contractive material and having a passage leading from the passage of the stopper into the glass bulb, said passage being at an intermediate part contracted to normally form a tight closure between the bottle and the bulb, the said contracted part being adapted to widen upon exertion of a lateral pressure thereon to open the passage, and a valve to close the discharge-opening of the bulb, substantially and for the 80 purpose as specified.

3. In a liquid or medicine measurer the combination with a hollow stopper fitting into the mouth of a bottle, of a glass bulb of a predetermined size to receive a prescribed quantity 85 of the liquid, a piece of contractive material between the stopper and the bulb, the said piece having at one end a hollow neck for its engagement with the stopper and at its opposite end a longitudinal projection for its connection with the bulb containing a passage open to the bulb and contracted at the end 90 which terminates in the hollow neck of said piece, and a valve to close the discharge-opening of the glass bulb, substantially and for the 95 purpose as specified.

4. In a liquid or medicine measurer or distributor the combination with a hollow stopper fitting into the mouth of a bottle, of a glass bulb of a predetermined size to receive a pre- 100 scribed quantity of the liquid, said bulb having at its one end a nozzle and at its opposite end a hollow neck, a piece of contractive material having at its one end a longitudinal projection fitting into the hollow neck of the 105 bulb and at its opposite end a hollow neck engaging the stopper, the said longitudinal projection having a passage open to the glass bulb and contracted at the end which terminates in the hollow neck of said piece, and a valve to 110 close the discharge-opening of the bulb, substantially and for the purpose as specified.

5. In a liquid or medicine measurer or distributor, the combination with a hollow stopper fitting into the mouth of a bottle, of a glass bulb of a predetermined size, to receive a prescribed quantity of the liquid contained in the bottle, said bulb having at one end a discharge-nozzle and at its opposite end a hollow-neck, 115 a hollow hump adjacent to the discharge-nozzle, a glass ball to close the inner end of the nozzle and to fit in its open position in the hollow hump, a piece of contractive material being at one end engaged with the hollow neck of the bulb and at its opposite end with the 120 hollow stopper, said contractive piece having a passage leading into the bulb, said passage being contracted at the end which terminates in the hollow stopper, substantially and for the 125 purpose as specified.

6. In a liquid or medicine distributer, the combination with a hollow glass stopper having a cork mantle on its outer surface to fit into the mouth of a bottle and a head on its outer end, a piece of contractive material and partially ball-shaped, having at one end a hollow neck to engage the head of the stopper and at its opposite end a cylindrical longitudinal projection, a glass bulb having a discharge-nozzle at one end and a hollow neck at its opposite end, the said hollow neck being adapted to receive the longitudinal projection of the contractive piece, having a passage open to the glass bulb and contracted at its end which terminates in the hollow neck of
- 5 said contractive piece, a hollow hump adjacent to the nozzle, a glass ball fitting upon the inner end of the nozzle and in the hollow hump, said ball being adapted to close the discharge-opening of the bulb when the bottle is 20 reversed and to rest in the hump when the liquid is discharged from the glass bulb, substantially as specified.
- 10 Signed at New York, in the county of New York and State of New York, this 2d day of 25 November, A. D. 1904.
- 15 LOUIS PEROTTI.
